H. EARL

GOLF BAG

Filed May 9, 1924

FIG. 2

FIG. 1

INVENTOR,
Norman Earl,
BY
Howard S. Smith,
Atty. ATTORNEY

UNITED STATES PATENT OFFICE.

HERMON EARL, OF PIQUA, OHIO.

GOLF BAG.

Application filed May 9, 1924. Serial No. 712,131.

This invention relates to new and useful improvements in golf bags, and has particular reference to a golf bag which is self-standing when in use.

5 It is the principal object of my invention to provide a simple and durable golf bag which, when the player is executing a stroke, will be supported in an upright position upon the ground. This obviates the necessity and inconvenience of the player stooping down to raise the bag after a drive, to carry it to the next playing position.

10 It is a further object of my invention to provide a golf bag provided with pivotal legs which are folded against the sides of the bag when the latter is being carried. By handle means which may be easily operated by the player, these legs may be moved outwardly to support the bag in an upright position during the execution of a golf stroke by the player.

15 In the accompanying drawings illustrating one form of embodiment of my invention, Figure 1 is a side elevational view of my golf bag in a self-standing position. And Figure 2 is a top plan view of the same.

20 Referring to the accompanying drawings, the numeral 1 designates a suitable golf club bag which in this instance is preferably made of leather covered metal such as aluminum. Slidably mounted on the upper part of the bag is a sleeve 2 constructed of aluminum or other suitable metal.

25 Projecting from the outer surface of the sleeve at suitable distances apart around it, are pairs of ears 3, 3. Pivotally secured between each pair of ears 3, 3 by a pin 4, is the upper end of a leg 5 that is preferably constructed of spring steel tubing. Pivotally secured by pins 6 to the middle portions of the legs 5, are the fork ends of swinging arms 7. Each one of said arms is hingedly secured at its inner end by a pin 8, between a pair of ears 9, 9 that project outwardly 30 from the outer surface of the lower part of the bag 1.

The legs 5, 5 just described are adapted to be forced outwardly to the inclined positions shown in full lines in Figure 1 to support the bag in an upright position when the latter is left on the ground by the player during the execution of a drive or other stroke. After the play is executed, the legs may be drawn inwardly to their dotted line positions in Figure 1, to assume such positions near the sides of the bag that they

will not interfere with the player's walking movement.

For the purpose of forcing the lower ends of the legs 5, 5 outwardly to their inclined 60 positions when the golf bag is set down, and to draw them inwardly when the bag is picked up, any suitable means may be employed such as the substantially oval-shaped handle 10 shown in Figure 1. This handle 65 is preferably integral with the sleeve 2, so that the latter may be raised and lowered by it to draw the legs 5, 5 inwardly and force them outwardly at the proper times. Preferably secured to the side of the bag 1 near 70 the handle 10, are two guide rails 11, 11 between which it is vertically movable and by which it is kept from twisting.

For the purpose of holding the sleeve 2 in a desired position, there are formed in the side of the bag 1 between the intersecting planes of the guide rails 11, 11, a series of radial holes 12. Formed in the handle 10 is a hole which is adapted to register with any one of the holes 12 in the bag, so that there 75 may project into a selected one of said holes 12 the inwardly turned end 13 of a curved locking member 14. Formed on the outer surface of the latter is an ear 15 which is pivoted within a concave recess formed in 80 the upper inner part of said handle. Between the outer upper end of the locking member 14 and the inner surface of said recess, a short compression spring 16 is inserted. When the handle 10 is grasped by 85 the hand of a player to lift the bag, the fingers of that hand may be pressed against the inner surface of the locking member 14 to withdraw its inwardly turned end 13 from a hole 12 in the bag, against the compression of the spring 16.

90 And then, when the handle is drawn upwardly to its uppermost position, or any other desired one, the pressure of the fingers upon the locking member 14 will be released to permit the 95 spring to force the locking end 13 of said member into the hole 12 opposite it in the bag, so that the legs 5, 5 may be maintained in the closed positions to which they have 100 been drawn by the handle. The lower surfaces of the arms 7 are preferably concaved to permit the legs 5, 5 to fit well into them when the latter are drawn to their inner 105 positions by the sleeve.

110 It will now be seen that when a player desires to set the bag upon the ground, the handle 10 may be unlocked by pressure upon

the inner surface of the locking member 14, whereupon the sleeve 2 may be forced downwardly a desired distance to extend the legs 5, 5 to a position which will make the bag 5 self-standing. Then, after a play has been completed, the player may return to the bag and pick it up without the necessity of stooping down to raise it from a position 10 parallel with the ground. After the handle 10 is grasped, an inward pressure upon the locking member 14 will permit the sleeve 2 to be elevated to draw the legs 5, 5 inwardly to their out-of-the-way positions.

I do not wish to be limited to the details 15 of construction and arrangement herein shown and described, and any changes or modifications may be made therein within the scope of the subjoined claims.

Having described my invention, I claim: 20
1. The combination with a golf bag, of a sleeve slidably mounted thereon, means pivotally secured to said sleeve to brace the bag for support in an upright position upon the ground, a handle on said sleeve, formed with 25 a hole in its side adjacent the bag, the latter having holes with which the hole in the

handle is adapted to be brought into registry, a locking member pivotally secured within the handle and having a projection adapted to pass through the hole therein for 30 entrance into any one of said holes in the bag, and resilient means inserted between the locking member and the handle, for the purpose specified.

2. The combination with a golf bag, of a 35 sleeve slidably mounted thereon, means pivotally secured to said sleeve to brace the bag for support in an upright position upon the ground, a handle on said sleeve, formed with a hole in its side adjacent the bag, the latter 40 having a series of vertically-arranged holes with which the hole in the handle is adapted to be brought into registry, a locking member pivotally secured within said handle and having a projection adapted to pass through 45 the hole therein for entrance into any one of said holes in the bag, and a spring inserted between the outer end of said locking member and the handle.

In testimony whereof I have hereunto set 50 my hand this 7th day of May, 1924.

HERMON EARL.
